CONTROLLER FOR INDUCTIVE DEVICES

John D. Leitch and Richard G. Widdows, Shaker Heights, Ohio, assignors to The Electric Controller & Manufacturing Company, Cleveland, Ohio, a corporation of Ohio

Application October 10, 1950, Serial No. 189,442

18 Claims. (Cl. 175—335)

1 This invention relates to an improved system for, and method of, controlling inductive devices, and more particularly to an improved control system and method for automatically effecting demagnetization of large inductive devices such as large lifting magnets in a short time.

It is common practice to magnetize a lifting magnet by connecting the magnet to a source of constant unidirectional voltage and to demagnetize the magnet by reversing the connections to the source through a resistor of fixed value which eventually limits the reverse current that flows to the magnet after the self-induced magnet voltage has decreased below the voltage of the source. The reverse current is interrupted automatically when the magnet flux is approximately zero. Full advantage of the operating efficiency of the larger lifting magnets now being used in increasing numbers by the steel and allied industries is not realized when the demagnetization of the larger magnets is controlled in the foregoing manner which has become common for smaller magnets. This is because the inductance to resistance ratio or time constant of the larger lifting magnets is so great that, when the larger magnets are controlled by conventional magnet controllers, the rate of flux decay is so slow that excessive dribbling of scrap iron and similar loads results. Furthermore, when the larger magnets are controlled in the usual manner, the time required to build up the flux to its maximum value and the time required to reduce the flux substantially to zero together constitute a relatively large portion of the overall operating cycle which generally includes attracting, lifting, transporting, and dropping of loads.

The build-up or magnetization time of the larger magnets has been decreased in some instances by overexciting the magnet during the attracting period and the initial portion of the lifting period of the operating cycle and reducing the excitation during the remainder of the lifting period and during the transporting period to prevent damaging overheating of the magnet. The use of two voltage values in this manner also reduces the energy stored in the magnet prior to demagnetization and therefore the demagnetization time is reduced slightly as compared to energizing with a fixed voltage, but this reduction in time is insufficient to reduce appreciably the excessive dribbling of the scrap material.

The magnet control system or automatic lifting magnet controller of the present invention effects complete demagnetization of even the largest lifting magnets in such a short time that scrap

5 iron or similar loads do not dribble off the magnet but instead drop quickly and substantially all at once. In fact, the demagnetization time obtained with the new controller is so short that it becomes a relatively unimportant part of the overall duty cycle. The improved magnet controller can provide a conventional energizing circuit or it can include equipment to provide the large initial voltage at the magnet for a time interval, thereby to cause the quick build-up of magnet flux, followed by the period of reduced voltage prior to demagnetization which prevents damaging over-heating of the magnet.

15 In one structure in which the present invention is embodied, demagnetization of a magnetized lifting magnet is initiated in the usual manner by closing a drop contactor just prior to opening of a lift contactor thereby to connect the magnet to the source in a reverse direction through a resistance in series therewith. In accordance with our invention, however, the value of this resistance is so selected in relation to the voltage of the source, the inductance and resistance of the magnet winding, and the arc quenching ability of the lift contactor that the voltage rise at the magnet terminals upon opening of the lift contactor approaches but does not exceed a maximum safe value. When the magnet voltage approaches line voltage, a relay responsive to the magnet voltage operates to reduce the resistance in series with the magnet. This reduced value of resistance is so selected in relation to the voltage of the source and the inductance and resistance of the magnet winding that the reverse current through the magnet increases as rapidly as possible without exceeding the rate at which it would interfere with the proper operation of an automatic interrupting means, thereby insuring interruption of the reverse current circuit before the magnet flux reverses. In one modification, the magnet circuit resistance is automatically increased before it is finally decreased. A further modification is a magnet controller which also provides a high initial energization to shorten the build-up time, the initial energization being subsequently reduced to prevent overheating of the magnet.

20 25 30 35 40 45 50 Although the invention is shown as an improvement of the type of magnet controller disclosed and claimed in Wright Reissue Patent No. 20,724 of May 10, 1938, its applicability to other types of automatic controllers for inductive devices is apparent.

An object of this invention is to provide an improved system and method for effecting rapid demagnetization of a large inductive device.

Another object is to provide an improved control system for, and method of, controlling an inductive device in which the resistance of the discharge resistor is changed during the demagnetization period in order to shorten the demagnetization time.

A further object is to provide a control system for an inductive device in which the resistance of the discharge resistor is reduced automatically at approximately the instant that the current flowing in the winding of the device reverses or becomes substantially zero.

A more detailed object is to provide a control system for an inductive device in which a voltage relay controls the resistance of the discharge path in accordance with the voltage at the terminals of the device.

A more specific object is to provide a controller for an inductive device in which the value of the resistance of the discharge circuit during reduction in the magnetizing current is so related to the energy stored in the device that the peak discharge voltage reaches but does not exceed a maximum safe value and in which the value of the resistance in series with the device during build-up of the reverse current is so related to the voltage of the source and the time constant of the device that the reverse current increases as rapidly as possible while still permitting automatic removal of the reverse voltage when the magnetic flux is approximately zero.

Other objects and advantages will become apparent from the following description wherein reference is made to the drawings, in which:

Fig. 1 is a wiring diagram of a preferred form of magnet control system;

Figs. 2 and 3 are wiring diagrams of respective modifications, and

Figs. 4 and 5 are graphs illustrating the operation of Figs. 1 and 2, respectively.

The illustrative embodiment of the control system shown in Fig. 1 is a lifting magnet controller comprising an electromagnetic lift contactor 10, an electromagnetic drop contactor 11, an electromagnetic resistor control contactor 12, a voltage relay 14, and a two-position master switch 15. The controller is arranged to be supplied from a suitable source of unidirectional voltage 16 through supply leads 17 and 18 which are also arranged to supply power from the source 16 to an inductive device such as a large lifting magnet 19 provided with a winding 19w having terminals 19a and 19b. Instead of a lifting magnet, the inductive device may be a large electromagnetic brake, clutch, chuck or similar apparatus having a highly inductive operating winding to be energized by direct current.

The contactor 10 may have an operating winding 10w, normally open main contacts 10a and 10b, normally open auxiliary contacts 10c and 10d, and normally closed auxiliary contacts 10e and 10f. A suitable means, such as a copper sleeve 10g surrounding the core of the contactor 10, is provided to delay the opening of the contactor 10 upon deenergization of the winding 10w. The contactor 11 may have an operating winding 11w, normally open main contacts 11a and 11b, and normally open auxiliary contacts 11c. The contactor 12 may have an operating winding 12w, normally open main contacts 12a and 12b, and normally closed auxiliary contacts 12c. The relay 14 may have an operating winding 14w and normally closed main contacts 14a and preferably is provided with suitable well-known means (not shown) to facilitate adjustment of its pick-

up and drop-out voltage values. The master switch 15 preferably has a pair of relatively stationary contacts 15a and 15b adapted to be bridged by a relatively movable contact 15c when the master switch is in the "drop" position as shown and indicated by a broken line D, and a pair of relatively stationary contacts 15d and 15e adapted to be bridged by the movable contact 15c when the master switch is in the "lift" position indicated by a broken line L. Any suitable form of master switch may be used which is capable of completing one circuit upon interruption of another, and vice versa, and which preferably is biased as by a spring (not shown) to the "drop" position.

A pair of resistors 20 may be connected in series with the winding 11w and a pair of resistors 21 may be connected in series with the winding 14w. Suitable means, such as a fixed resistor 24 and an adjustable resistor 25 connected in series with each other and in parallel with the winding 11w, are provided to control the drop out of the contactor 11. Resistors 28 through 31 are interposed in series with each other in a discharge and reverse current circuit for the magnet 19. Preferably, the resistors 28 and 30 have approximately the same resistance, and likewise the resistors 29 and 31 have approximately the same resistance.

Operation of Fig. 1

Further understanding of the embodiment of Fig. 1 can be had from the following brief and detailed descriptions of its operation. Briefly, the magnet 19 is magnetized by moving the master switch contact 15c to the lift position L which causes the contacts 10a and 10b to close and connect the winding 19w directly across the supply lines 17 and 18. The magnet 19 may be demagnetized by returning the contact 15c to the drop position D which causes closure of the contacts 11a and 11b followed by opening of the contacts 10a and 10b. This causes the voltage at the magnet terminals 19a and 19b to reverse and increase suddenly whereby current continues to flow in the same direction through the winding 19w, the circuit being completed through the contacts 11a and 11b, the resistors 28, 29, 30 and 31 and the source 16. The increased voltage between the terminals 19a and 19b causes pick up of the relay 14 and thereafter decreases exponentially and, when it approaches the voltage of the source 16, the relay 14 drops out to cause the contactor 12 to close its contacts 12a and 12b. This reduces the resistance in series with the magnet by shunting the resistors 29 and 31 so that after the voltage between the terminals 19a and 19b becomes less than the voltage of the source 16, the magnet current builds up rapidly in the reverse direction. The voltage between the terminals 19a and 19b becomes less than the voltage of the source because of the voltage drops across the resistors 28 and 30 which increases with increase in the reverse current. When the voltage across the terminals 19a and 19b reaches a low value indicative of zero flux in the magnet and determined by adjustment of the resistor 25, the contactor 11 drops out to interrupt the reverse current circuit.

Considering now the operation of the embodiment of Fig. 1 in more detail, movement of the master switch contact 15c to the lift position L completes an energizing circuit for the winding 10w from the supply line 17 through the contacts 15d, 15c, 15e and 12c and the winding 10w to the supply line 18. The contactor 10 responds

immediately upon energization of its winding 16w to close its contacts 10a, 10b, 10c, and 10d and to open its contacts 10e and 10f. Closure of the contacts 10c and 10d completes a portion of an energizing circuit for the winding 11w later to be fully completed upon return of the contact 15c to the drop position D. Opening of the contacts 10e disconnects the winding 11w from the magnet terminal 19a so that no current can flow in the winding 11w while the contact 15c is in the lift position L. Opening of the contacts 10f insures that an energizing circuit for the winding 12w cannot be completed until after the contactor 10 has dropped out. Closure of the contacts 10a and 10b completes an energizing circuit for the magnet 19 from the supply line 17 through the contacts 10a, the terminal 19a, the winding 19w, the terminal 19b, and the contacts 10b to the supply line 18. The current in the magnet winding 19w now increases exponentially from zero in the direction of the arrow 32 at a rate dependent upon the inductance to resistance ratio of the winding 19w and the magnitude of the voltage of the source 16 to a final steady value determined by the resistance of the winding 19w and the voltage of the source 16. This final steady current value is indicated by a horizontal line 34 in Fig. 4 wherein current in the winding 19w is plotted against time. The winding 19w preferably is so selected that when operated on a known duty cycle and carrying the current 34 during its energized period, the magnet 19 will eventually reach but not exceed a maximum safe temperature.

Although the winding 14w is now connected across the supply lines 17 and 18 in series with the resistors 21, the relay 14 is selected and adjusted so that it does not pick up at this time.

The energized magnet 19 may now attract, lift, and transport a load (not shown). When it is desired to demagnetize the magnet 19 to drop the load, the master contact 15c is permitted or caused to return to the drop position D. This interrupts the energizing circuit for the winding 16w at the contacts 15d and 15e and completes the energizing circuit for the winding 11w from the supply line 17, the contacts 15d, 15b, 15c, and 15a, a conductor 35, the still closed contacts 10c, the winding 11w, and the still closed contacts 10d to the supply line 18. In response to energization of its winding 11w, the contactor 11 closes its contacts 11a, 11b, and 11c. Although the energizing circuit to the winding 16w has been interrupted, the action of the copper sleeve 10g causes the contactor 10 to remain in its energized position for a time interval to insure that the contacts 11a and 11b close before the contacts 10a and 10b open. The contacts 11c are in the energizing circuit for the winding 12w but their closure does not complete this circuit because the contacts 10f are still open. Closure of the contacts 11a connects the series connected resistors 28 and 29 in parallel with the magnet winding 19w, and closure of the contacts 11b connects the series connected resistors 30 and 31 in parallel with the winding 19w. This has no effect on the current in the winding 19w.

The copper sleeve 10g delays drop out of the contactor 10 just long enough for the contacts 11a and 11b to close. Drop-out of the contactor 10 causes opening of the contacts 10a and 10b which disconnects the terminal 19a from the supply line 17 and the terminal 19b from the supply line 18, but, since the contacts 11a and 11b are now closed, the winding 19w remains connected to the supply lines in a discharge and reverse

current circuit which is from the supply line 17 through the resistors 31 and 30, the contacts 11b, the terminal 19b, the winding 19w, the terminal 19a, the contacts 11a, and the resistors 28 and 29 to the supply line 18. The voltage between the terminals 19a and 19b upon opening of the contacts 10a and 10b suddenly reverses and, due to the self-inductance of the winding 19w, increases to a value far above that of the source 16, and the current in the winding 19w continues to flow in the direction of the arrow 32 through the discharge and reverse current circuit just traced. Although the contacts 10c and 10d open upon drop-out of the contactor 10, the winding 11w remains energized because the concurrent closure of the contacts 10e connects the winding 11w across the terminals 19a and 19b in series with the resistors 20.

The maximum value of the voltage at the terminals 19a and 19b upon opening of the contacts 10a and 10b is dependent upon the time required to extinguish the arcs at the contacts 10a and 10b, the voltage of the source 16, the inductance of the winding 19w, and the total resistance of the winding 19w and the series connected resistors 28, 29, 30, and 31. Preferably, the contactor 10 is selected so that arcs persist at the contacts 10a and 10b long enough to maintain the voltage at the terminals 19a and 19b materially below the value it would reach if no or little arcing occurred. The arcs thus dissipate some of the magnetic energy stored in the winding 19w and permit the use of a higher discharge circuit resistance which permits quicker demagnetization.

Consequently upon the sudden reversal and increase of the voltage at the terminals 19a and 19b, the relay 14 picks up to open its contacts 14a. The contacts 14a are in the energizing circuit for the winding 12w but they open so soon after the contacts 10f close that the winding 12w does not become operatively energized even momentarily at this time.

Assuming that the arcs on contacts 10a and 10b are interrupted at time t_1 in Fig. 4, the current in the winding 19w starts at time t_1 to decrease exponentially as indicated by the curve 36. The resistors 29 and 31 are so selected that the total resistance of the resistors 28, 29, 30, and 31 when all are in series is such as to permit the initial decrease of current in the winding 19w to be as rapid as possible without causing a damaging voltage rise. Thus, the slope of curve 36 is made as steep as possible by causing the resistance of the discharge and reverse current circuit to be as large as possible, the maximum value being determined by the maximum peak voltage that can be withstood safely by the insulation of the winding 19w.

When the magnet discharge current reaches a value indicated at 37, the voltage between the terminals 19a and 19b has decreased to a voltage only slightly in excess of the voltage of the source 16. The relay 14 is adjusted to drop out when the voltage at the terminals 19a and 19b reaches this value. Drop out of the relay 14 causes closure of the contacts 14a which completes the energizing circuit for the winding 12w from the supply line 17, the contacts 15d, 15b, 15c, 15a, 10f, 14a, and 11c through the winding 12w to the supply line 18. The contactor 12, in response to energization of its winding 12w, closes its contacts 12a and 12b and opens its contacts 12c. Opening of the contacts 12c prevents operation of the contactor 10 while the contactors

11 and 12 are picked up thereby to prevent large currents from flowing in the resistors 28 and 30 which are of relatively low ohmic value. Closure of the contacts 12a and 12b short circuits the resistors 29 and 31, respectively. If the voltage between the terminals 19a and 19b has not become equal to the voltage of the source 16 when the contacts 12a and 12b close, the magnet current decreases further as indicated by the curve 38.

When the contacts 12a and 12b close or shortly thereafter, the voltage between the terminals 19a and 19b becomes equal to the voltage of the source 16 and the magnet current reaches zero as indicated at t_2 in Fig. 4. The current in the winding 19w then starts to increase in the reverse direction or in the direction of the arrow 31 in Fig. 1. The resistance of the resistors 28 and 29 is sufficiently low so that the reverse current builds up as rapidly as possible thereby to reduce the remanent magnetism to zero in as short a time as possible consistent with proper operation of the contactor 11. The rise in reverse current is indicated by a curve 39 in Fig. 4. The rise in reverse current is accompanied by a further decrease in the voltage between the terminals 19a and 19b. The resistor 25 is so adjusted according to the magnetic properties of the load being handled that the contactor 11 drops out to open its contacts 11a, 11b, and 11c when the reverse current reaches a value corresponding to substantially zero flux in the magnet 19 which is indicated at t_3 in Fig. 4. Opening of the contacts 11c causes deenergization of the winding 12w and opening of the contacts 11a and 11b disconnects the winding 19w from the supply leads 17 and 18. The reverse current circuit is thus interrupted at or near the point of zero flux and the magnet 19 remains substantially demagnetized until the contactor 10 is again operated.

By properly selecting the value of the resistance in series with the magnet at the initiation of discharge and causing the contactor 12 to reduce this resistance to a very low value at the proper time during the demagnetizing cycle, the time required for complete demagnetization is made very short and dribbling of loads is thereby prevented. For example, a 230 volt magnet having a resistance of 2.5 ohms and an inductance of approximately 20 henries when loaded with scrap requires about 6 seconds to completely drop the load when a discharge resistance of 15 ohms is used throughout the demagnetization cycle, whereas, when the discharge resistance is changed from 20 to 4 ohms during the demagnetization cycle as herein described, the demagnetization time is only about 2 seconds. This shorter time prevents dribbling of the load, permits it to be accurately placed, and speeds up the material handling operation.

Although in Fig. 1 the closure of the contactor 12 is controlled by the voltage relay 14, it is apparent that a relay directly responsive to the magnitude of the magnet current could be used instead if desired. It is also apparent that other well-known means could be used to interrupt the reverse current circuit at the proper time.

Modification—Fig. 2

In the modification of Fig. 2, wherein control elements which may be the same as those of Fig. 1 are referred to by the same reference characters, the resistor 29 of Fig. 1 is replaced by a pair of series connected resistors 40 and 41 and the resistor 31 is replaced by a pair of series-con-

nected resistors 42 and 43. A lift contactor 45 is similar to the contactor 10 of Fig. 1 in that it may have main contacts 45a and 45b interposed in the energization circuit for the magnet 19, normally closed auxiliary contacts 45e and 45f, an operating winding 45w, and a copper sleeve 45g. The contactor 45 differs from the contactor 10 in that in addition to normally open auxiliary contacts 45c and 45d it may have also normally open auxiliary contacts 45h. The contacts 45h control the energization of a winding 46w of an electromagnetic resistor control contactor 46 which may have normally open main contacts 46a and 46b and normally closed auxiliary contacts 46c. Drop out of the contactor 46 is preferably delayed for a time interval after deenergization of its winding 46w by any suitable means shown as a resistor 48 and capacitor 49 connected in series with each other in parallel with the winding 46w. The contacts 46a and 46b when closed short circuit the resistors 40 and 42, respectively.

The contactor 12 of Fig. 1 is replaced in Fig. 2 by an electromagnetic resistor control contactor 50 which may have an operating winding 50w, normally open main contacts 50a and 50b, normally closed auxiliary contacts 50c, and normally open auxiliary contacts 50d. The contacts 50a and 50b when closed short circuit the resistors 41 and 43, respectively.

Operation of Fig. 2

Further understanding of the embodiment of Fig. 2 can be had from the following brief and detailed description of its operation. The magnet 19 in Fig. 2 is energized by moving the master switch contact 15c to the lift position L which causes closure of the contacts 45a and 45b connecting the winding 19w directly across the supply lines 17 and 18. The magnet 19 may be deenergized by returning the contact 15c to the drop position D which causes closure of the contacts 11a, 11b, 46a, and 46b followed by opening of the contacts 45a and 45b. The magnet 19 now starts to discharge through the resistors 28, 30, 41 and 43 in series. The contacts 45h open when the contacts 45a and 45b open, and shortly thereafter the contacts 46a and 46b open to insert the additional resistors 40 and 42 in series with the magnet 19. When the voltage across the terminals 19a and 19b approaches the voltage between the supply leads 17 and 18, the relay 14 drops out to cause closure of the contacts 50a and 50b which is followed immediately by re-closure of the contacts 46a and 46b. This reduces the resistance in series with the magnet by shunting the resistors 40, 41, 42, and 43 and the magnet current builds up rapidly in the reverse direction. When the voltage across the magnet terminals 19a and 19b reaches a predetermined low value, the contactor 11 drops out to interrupt the reverse current circuit.

Considering now the operation of the magnet controller of Fig. 2 in more detail, movement of the master switch contact 15c to the lift position L completes an energizing circuit for the winding 45w from the supply line 17 through the contacts 15d, 15c, 15e, 50c, 46c, and the winding 45w to the supply line 18. The contactor 45 in response to energization of its winding 45w closes its contacts 45a, 45b, 45c, 45d, and 45h and opens its contacts 45e and 45f without time delay. Closure of the contacts 45a, 45b, 45c, and 45d and opening of the contacts 45e and 45f results in completion and interruption of cir-

cuits as in the case of the corresponding contacts of the contractor 10 in the embodiment of Fig. 1. Closure of the contacts 45h which are in an energizing circuit for the winding 46w permits that winding to be energized upon return of the contact 15c to the drop position D. With the contacts 45a and 45b closed, the current in the magnet winding 19w increases exponentially from zero in the direction of the arrow 32 until it reaches a final steady value indicated at 34 in Fig. 5 wherein current in the winding 19w when controlled by the controller of Fig. 2 is plotted against time as in Fig. 4.

When the contact 15c is returned to the drop position D, the energizing circuit for the winding 45w is interrupted at the contacts 15d and 15e and an energizing circuit for the winding 11w is completed from the supply line 17, the contacts 15d, 15b, 15c, and 15a, a conductor 35, the now closed contacts 45e, the winding 11w, and the now closed contacts 45d to the supply line 18. The energizing circuit for the winding 46w is concurrently completed from the now energized conductor 35 through the contacts 45h and the winding 46w to the supply line 18, and the capacitor 49 in parallel with the winding 46w quickly accumulates a charge.

In response to energization of the windings 11w and 46w, the contacts 11a, 11b, 11c, 46a and 46b close and the contacts 46c open. Closure of the contacts 11c does not complete an energizing circuit for the winding 50w since this circuit is open at the contacts 45f. Closure of the contacts 11a connects the series connected resistors 28 and 41 in parallel with the magnet winding 19w, the concurrent closure of the contacts 46a short circuiting the resistor 40, and similarly closure of the contacts 11b connects the series connected resistors 30 and 43 in parallel with the magnet winding 19w, the concurrent closure of the contacts 46b short circuiting the resistor 42.

Shortly after the contacts 11a and 11b close, the contractor 45 drops out to open its contacts 45a and 45b which disconnects the terminal 19a from the supply line 17 and the terminal 19b from the supply line 18. The winding 19w, however, remains connected to the supply lines in a reverse sense in a discharge and reverse current circuit from the supply line 17 through the contacts 46b, the resistors 43 and 30, the contacts 11b, the terminal 19b, the terminal 19a, the contacts 11a, the resistors 28 and 41, and the contacts 46a to the supply line 18. The resistors 28, 30, 41, and 43 are so selected that their combined resistance when connected in series is such that, with arcs existing for a time interval at the contacts 45a and 45b, the self-induced voltage at the terminals 19a and 19b substantially reaches but does not exceed a maximum safe voltage. After the arcs are interrupted, the current in the winding 19w starts to decrease at a rate indicated by a curve 52 in Fig. 5.

The contacts 45h open when the contractor 45 drops out to disconnect the winding 46w from the supply lines 17 and 18, but the contractor 46 remains in its picked up position for a time interval while the capacitor 49 discharges through the winding 46w. The time delay period of the contractor 46 and the resistance of the resistors 40 and 42 are so selected as to permit the energy in the winding 19w to decrease to a value such that upon opening of the contacts 46a and 46b the resistance in the magnet circuit is increased sufficiently to cause the self-induced voltage at the terminals 19a and 19b to again reach a maxi-

mum safe value. When the contacts 46a and 46b open, the magnet current has decreased to a value indicated at 54 in Fig. 5 and thereafter the magnet current starts to decrease more rapidly as indicated by the curve 55.

When the magnet current reaches a value indicated at 56, the relay 14, which picked up when the contacts 45a and 45b opened, drops out to reclose its contacts 14a to complete an energizing circuit for the winding 50w from the energized conductor 35 through the contacts 45f, 14a, and 11c and the winding 50w to the supply line 18. The contractor 50 thereupon closes its contacts 50a, 50b, and 50d and opens its contacts 50c. Opening of the contacts 50c prevents inadvertent re-energization of the winding 45w. Closure of the contacts 50d completes an energizing circuit for the winding 46w from the energized conductor 35 through the contacts 50d and the winding 46w to the supply line 18. Consequently, closure of the contacts 50a and 50b is quickly followed by closure of the contacts 46a and 46b, and the resistors 40, 41, 42, and 43 are all short circuited practically at the same instant. This causes the change in rate of current delay indicated at 56 in Fig. 5. When the voltage at the terminals 19a and 19b becomes less than the supply voltage, the current which had decreased from the point 56 reverses direction and increases as indicated by a curve 58. The resistance of the resistors 28 and 29 is such that the rate of increase of the reverse current is a maximum consistent with proper drop out of the contractor 11 when the voltage across the terminals 19a and 19b reaches a predetermined low value.

Opening of the contacts 11a and 11b upon drop out of the contractor 11 disconnects the winding 19w from the supply conductors 17 and 18 and opening of the contacts 11c deenergizes the winding 50w. The contractor 50 then opens its contacts 50d to deenergize the winding 46w. The contacts 50c reclose immediately, but the contractor 45 cannot be operated again until the contacts 46c reclose.

When the embodiment of Fig. 2 has been used with the specific magnet hereinbefore referred to, it has been found desirable to use an original discharge resistance of about 20 ohms which is increased to about 50 ohms before being reduced to a final value of about 4 ohms.

Since in Fig. 2 the resistance of the discharge circuit is increased and then decreased during the demagnetization period, the embodiment of Fig. 2 provides a somewhat shorter demagnetization time than does the embodiment of Fig. 1. The latter is preferred, however, because of its simplicity.

Modification—Fig. 3

The embodiment of Fig. 3 shows how the embodiment of Fig. 1 may be modified to provide a decreased build up time for the magnet 19, and control elements which may be identical in the two embodiments are referred to by the same reference characters. It will become apparent from the description of Fig. 3 that the embodiment of Fig. 2 can readily be modified in a like manner. In Fig. 3 the voltage applied to the magnet 19 is varied somewhat in the manner disclosed in Yorkey Patent No. 2,257,361 and the voltage values relative to the resistance and heat dissipating ability of the magnet are preferably chosen as therein described to obtain the advantages of that patent in addition to those set forth herein.

The magnet controller of Fig. 3 comprises an electromagnetic lift contactor 60, an electromagnetic drop contactor 61, an electromagnetic resistor control contactor 62, an electromagnetic voltage control contactor 64, an electromagnetic time delay relay 65, and the relay 14. Instead of the master switch 15, the controller of Fig. 3 includes a lift push button 66 having normally open contacts 66a and a drop push button 68 having normally open contacts 68a and normally closed contacts 68b and 68c. Preferably, the push button 66 is biased to its open position by a strong spring 66s making it difficult to hold the push button 66 in closed position. The supply conductors 17 and 18 in Fig. 3 are arranged to be connected to a suitable direct current generator 70 through a circuit including series connected resistors 71 and 72 when a double pole knife switch 74 is closed.

The lift contactor 60 may have an operating winding 60w, normally open main contacts 60a and 60b, normally open auxiliary contacts 60c, 60d, and 60h, normally closed auxiliary contacts 60e and 60f, and a copper sleeve 60g. The drop contactor 61 may have an operating winding 61w, normally open main contacts 61a and 61b, normally open auxiliary contacts 61c, and normally closed auxiliary contacts 61d. The resistor control contactor 62 may have an operating winding 62w, normally open main contacts 62a and 62b, normally closed auxiliary contacts 62c, and normally open auxiliary contacts 62d and 62e. The voltage control contactor 64 may have an operating winding 64w, normally open main contacts 64a, and normally open auxiliary contacts 64b. The time delay relay 65 may have an operating winding 65w, normally closed main contacts 65a, and a suitable time delay means such as a dash pot 65b for delaying reclosure of the contacts 65a.

Operation of Fig. 3

The following brief description of the operation of Fig. 3 is followed by a more detailed description.

With the knife switch 74 closed, closure of the lift push button 66 causes pick up of the voltage control contactor 64. This results in an increase of the voltage between the supply conductors 17 and 18 and causes pick up of the lift contactor 60. The increased voltage is so related to the resistance of the winding 19w and the heat dissipating ability of the magnet 19 that if it were continued throughout the energized portion of the duty cycle of the magnet 19, the magnet 19 would become overheated in a relatively short time as explained in the Yorkey patent. The magnet when overenergized by the increased voltage builds up to its normal full voltage strength in a very short time. Depending upon the type of load being handled, the contacts 66a may be held closed for an interval sufficient to allow the magnet to attract and separate a large load. Release of the push button 66 causes drop out of the contactor 64, but the contactor 60 remains in its picked up position. The voltage between the supply conductors 17 and 18 is now sufficiently reduced so that the magnet 19 cannot become overheated but not to the extent that any of the attracted load is dropped as explained in the aforementioned Yorkey patent.

Demagnetization of the magnet 19 is effected by operating the push button 68. This causes the drop contactor 61 to pick up followed by drop out of the contactor 60. The current in

the winding 19w now decreases, but, before it reverses, the contactor 62 picks up to reduce the resistance in series with the winding 19w. Pick up of the contactor 62 also causes reclosure of the contactor 64 for a time interval determined by the relay 65. The resultant momentary increase of reverse voltage causes a rapid rise of reverse current. Before the magnet flux reaches zero, the contactor 64 drops out to reduce the reverse voltage so that the reverse current thereafter increases more slowly to insure proper operation of the contactor 61 which is adjusted to drop out to disconnect the magnet from the source 70 before the magnet flux can reverse.

Considering now the operation of the embodiment of Fig. 3 in detail, closure of the push button 66 with the switch 74 closed completes an energizing circuit for the winding 64w from the supply lead 17 through the contacts 68b, 66a, and 65a and the winding 64w to the supply lead 18. The contactor 64 thereupon responds to close its contacts 64a and 64b. Closure of the contacts 64a short circuits the resistor 72 and the voltage between the supply leads 17 and 18 immediately increases. Closure of the contacts 64b completes an energizing circuit for the winding 60w from the supply line 17 through the contacts 68c, 64b, and 62c and the winding 60w to the supply line 18. The contactor 60 thereupon picks up and its contacts 60a, 60b, 60c, 60d, 60e, and 60f function like the corresponding contacts of the contactor 10 in Fig. 1. The contacts 60h also close to complete a holding circuit for the winding 60w from the supply lead 17 through the contacts 60h, 61d, and 62c to the winding 60w. The increased voltage between the supply leads 17 and 18 is impressed on the winding 19w and the magnet flux increases rapidly. The relay 14 is adjusted so that it does not pick up at this time.

When a load (not shown) has been attracted and separated from a pile by the magnet 19, the push button 66 is released to permit the spring 66s to open the contacts 66a which deenergizes the winding 64w. The contactor 60 remains in its energized position after the contacts 64b open because of the previously traced holding circuit, but opening of the contacts 64a reduces the voltage applied to the winding 19w by inserting the resistor 72 in series with the generator 70. The reduction in voltage at the terminals 19a and 19b is sufficient to prevent overheating of the magnet 19 but is insufficient to permit the magnet 19 to drop its load.

Automatic demagnetization of the magnet 19 is initiated by operation of the push button 68 to close the contacts 68a and to open the contacts 68b and 68c. Opening of the contacts 68c prevents reenergization of the winding 60w by subsequent closure of the contacts 64b and opening of the contacts 68b prevents reenergization of the winding 64w through the contacts 66a should they be inadvertently reclosed. Closure of the contacts 68a completes an energizing circuit through the conductor 35 for the winding 61w which is like a similar circuit in Fig. 1. The contacts 61a, 61b, and 61c function like the corresponding contacts of the contactor 11 in Fig. 1, and the contacts 61d open to interrupt the only remaining circuit for winding 60w. The contactor 60 drops out after a brief time delay period and the magnet 19 starts to discharge through the resistors 28, 29, 30, 31, 72 and 71 and the source 70.

The resulting rise in voltage at the terminals 19a and 19b causes pick up of the relay 14. When the magnet voltage decreases to a value nearly

equal to the reduced voltage between the supply leads 17 and 18, the relay 14 drops out to complete an obvious energizing circuit for the winding 62w and the contactor 62, then responds to short circuit the resistors 29 and 31. The contacts 62d and 62e close upon pick up of the contactor 62 to complete energizing circuits for the windings 64w and 65w. The circuit for the winding 64w is from the supply lead 17 through the contacts 62d and 65a and the winding 64w to the supply lead 18. The circuit for the winding 65w is from the supply lead 17 through the contacts 62d and 62e and the winding 65w to the supply lead 18. The contactor 64 responds immediately to close its contacts 64a which effects an increase in the voltage between the leads 17 and 18. This increased voltage causes the reverse current to increase very rapidly. The relay 65 responds an instant later to open its contacts 65a which de-energizes the winding 64w. The contactor 64 again drops out and the voltage at the terminals 19a and 19b again decreases so that the rate of increase of reverse magnet current is not too great to prevent proper operation of the contactor 61 which subsequently drops out as described in connection with the contactor 11 in Figs. 1 and 2.

We claim:

1. A system for controlling the operation of an inductive device designed for operation at a predetermined value of unidirectional voltage comprising a magnetizing circuit, a highly resistive discharge circuit, a low resistive reverse current circuit, magnetizing switch means operable to connect said device to a source of said unidirectional voltage through said magnetizing circuit for magnetizing said device, discharge switch means operable to connect said device to said source in a reverse direction through said highly resistive discharge circuit, means for closing said magnetizing switch means, means for operating said discharge switch means to complete said discharge circuit from the source of the magnet while said magnetizing switch means is closed and for subsequently effecting interruption of said magnetizing circuit while the discharge circuit remains completed, whereby the voltage existing across said device suddenly reverses to become opposed to the voltage of the source, then increases, and then declines exponentially, additional switch means operative for connecting said device to said source through said reverse current circuit while maintaining said opposed relation of said voltages, whereby, upon decline of said reversed voltage below the voltage of said source, a reverse current can flow through said reverse current circuit from said source to said device, and means operative to effect disconnection of said device from said source when the magnetic flux of said device is approximately zero.

2. A control system in accordance with claim 1 characterized in that electroresponsive means are provided which are connectible in a circuit with said device and, when so connected, are rendered operative in response to the electrical condition of said device while said reversed voltage is declining, and, when operative, render said additional switch means operative.

3. A control system in accordance with claim 2 characterized in that said electroresponsive means comprises an electromagnetic relay.

4. A control system in accordance with claim 1 characterized in that the relatively large resistance of said discharge circuit is so related to

the magnetic energy that can be stored in said device, when the device is magnetized through said magnetizing circuit, that the maximum value of said reversed voltage can closely approach but not exceed the maximum peak voltage capable of safely being withstood by said device.

5. A control system in accordance with claim 4 characterized in that interruption of said magnetizing circuit is accompanied by arcing, and the relatively large resistance of said discharge circuit is so related to the magnetic energy that can remain stored in said device after said arcing terminates, that the maximum value of said reversed voltage can closely approach but not exceed the maximum peak voltage capable of being safely withstood by said device.

6. A control system in accordance with claim 1 characterized in that said means for interrupting said reverse current circuit is responsive to a predetermined magnitude of said reverse current and is positively operative only when the rate of rise of said reverse current is below a predetermined maximum rate of rise, and the low resistance of said reverse current circuit is so related to the resistance and inductance of said device and to said value of unidirectional voltage that the rate of rise of said reverse current can approach but not exceed said predetermined maximum rate of rise.

7. A control system in accordance with claim 1 characterized in that the relatively large resistance of said discharge circuit is so related to the magnetic energy that can be stored in said device, when the device is magnetized through said magnetizing circuit, that the maximum value of said reversed voltage can closely approach but not exceed the maximum peak voltage capable of safely being withstood by said device, said means for interrupting said reverse current circuit is responsive to a predetermined magnitude of said reverse current and is positively operative only when the rate of rise of said reverse current is below a predetermined maximum rate of rise, and the low resistance of said reverse current circuit is so related to the resistance and inductance of said device and to said value of unidirectional voltage that the rate of rise of said reverse current can approach but not exceed said predetermined maximum rate of rise.

8. A system for controlling an inductive device designed to operate at a predetermined value of unidirectional voltage, comprising magnetizing switch means for connecting said device to a source of said voltage in a magnetizing circuit for magnetizing said device, resistance means, switch means operable to connect said device in a discharge and reverse current circuit including said resistance means, means for operating said discharge switch means to complete said discharge and reverse current circuit while said magnetizing circuit is completed, and for subsequently interrupting said magnetizing circuit whereby the voltage existing across said device suddenly reverses and rises in value and then decreases in value exponentially, and means operative to reduce the resistance of said resistance means while said reversed voltage is decreasing.

9. A system for controlling an inductive device comprising a switch for admitting an energizing current to the device to produce a magnetic flux in the device, a second switch for setting up reverse current connections to the device, and magnetically operated means for causing opening of said first mentioned switch, and for causing closing of said second mentioned switch to set

15

up said reverse current connections before said first mentioned switch can open and interrupt said energizing current, a variable resistor in said reverse current connections, said reverse current connections being operative to admit a reverse current to said device for neutralizing said magnetic flux after said magnetic flux has decreased a predetermined amount, and means operative to reduce the resistance of said resistor prior to admission of said reverse current.

10. The combination with an inductive device, a source of unidirectional voltage, two resistors, a pair of contacts, a circuit connecting the contacts and device in series to said source, means for connecting the device and one of its said series connected contacts in parallel with one of said resistors, means for connecting the device and the other of its series connected contacts in parallel with the other of said resistors, and means for opening said contacts whereby the winding remains connected to said source in series with said resistors, of means operable for short circuiting a portion of each of said resistors, and means rendered operative, by an electrical condition of said device resulting from opening of said contacts, to operate said last mentioned means prior to the reversal of the flow of current in the device.

11. In a control system for a lifting magnet, a source of power, switching means for connecting the winding of the lifting magnet directly to the source of power, resistance means, reverse switching means operable to connect the winding to said source, through said resistance means, for applying reverse power to said winding, electromagnetic switching means operable to reduce the resistance of said resistance means, electromagnetic operating means for said switching means connected to the winding and being responsive to an electrical condition in said winding, resulting from the said application of reverse power, for operating said electromagnetic switching means, and means for rendering said reverse switching means inoperative.

12. In a magnet and control system, a lifting magnet to be connected to and disconnected from a source of power, a variable discharge resistor so related to the magnet as to be capable of preventing the occurrence of high induced voltages upon deenergization of the magnet resulting from disconnection of the magnet from the source of power, electromagnetic switching means selectively operable to connect and disconnect the magnet to and from the source of power, means for connecting said discharge resistor between the magnet and the source of power, magnetic operating means responsive to the voltage at the magnet while the magnet is connected to the source of power through said discharge resistor for reducing the resistance of said resistor, and magnetic operating means responsive to the voltage at said magnet after the resistance of said resistor has been reduced for disconnecting said magnet from the source of power.

13. A control system in accordance with claim 1 characterized in that means are provided for reducing the voltage impressed on said magnetizing circuit from said source after said magnetizing circuit is completed and before operation of said discharge switch means.

14. The method of operating a lifting magnet which comprises the steps of connecting the magnet to a source of unidirectional voltage for magnetizing the magnet to lift a load, subsequently, while maintaining the first connection, connecting the magnet in a reverse direction to said

5
10

source through resistance, breaking the first connection after the second connection is completed, whereby the voltage at the magnet suddenly reverses and increases to a maximum value and then starts to decrease exponentially, and, when said voltage at the magnet is approximately equal to the voltage of said source, decreasing the said resistance, and then breaking the second connection after said voltage at the magnet becomes less than the voltage of said source.

15. A system for controlling an inductive device designed to operate at a predetermined value of unidirectional voltage, comprising magnetizing switch means for connecting said device to a source of said voltage in a magnetizing circuit for magnetizing said device, resistance means, switch means operable to connect said device in a demagnetizing and reverse current circuit including said resistance means, means for operating said demagnetizing switch means to complete said demagnetizing and reverse current circuit while said magnetizing circuit is completed, and for subsequently interrupting said magnetizing circuit whereby the voltage existing across said device suddenly reverses and rises in value and then decreases in value exponentially, means operable to increase and then decrease the resistance of said resistance means in sequence while said reversed voltage is decreasing, and means rendered operative in response to the electrical condition of the magnet to operate said last mentioned means.

16. The method of operating a lifting magnet designed for operation at a predetermined normal value of unidirectional voltage which will cause a predetermined normal safe current to flow in the magnet depending upon the temperature of the magnet, said method comprising the steps of connecting the magnet in a magnetizing circuit to a source of power to impress on the magnet a unidirectional voltage higher than said normal value of voltage for causing the magnetizing current in the magnet to increase rapidly from zero, reducing the voltage impressed on the magnet to said normal value of voltage approximately when the magnetizing current reaches the value of said normal current, subsequently connecting the magnet in a discharge and reverse current circuit to the source through a resistor, interrupting said magnetizing circuit after said discharge and reverse current circuit is completed, whereby the voltage at the magnet suddenly reverses, increases to a maximum value and then starts to decrease exponentially, then, when said magnet voltage is approximately equal to said normal value of voltage, decreasing the resistance of said resistor and then, after said magnet voltage becomes less than said normal value of voltage, interrupting said discharge and reverse current circuit.

17. The method of operating a lifting magnet designed for operation at a predetermined normal value of unidirectional voltage which will cause a predetermined normal safe current to flow in the magnet depending upon the temperature of the magnet, said method comprising the steps of connecting the magnet in a magnetizing circuit to a source of power to impress on the magnet a unidirectional voltage higher than said normal value of voltage for causing the magnetizing current in the magnet to increase rapidly from zero, reducing the voltage impressed on the magnet to said normal value of voltage approximately when the magnetizing current reaches the value of said normal current, subsequently connecting the magnet in a discharge and reverse current circuit to the

75

source through a resistor to impress said normal value of voltage on the discharge and reverse current circuit, interrupting said magnetizing circuit after said discharge and reverse current circuit is completed, whereby the voltage at the magnet suddenly reverses, increases to a maximum value and then starts to decrease exponentially, increasing the voltage impressed on said discharge and reverse current circuit when said magnet voltage is in the neighborhood of said increased voltage, and interrupting said discharge and reverse current circuit after said magnet voltage becomes materially less than said normal value of voltage.

18. A system for controlling an inductive device designed to operate at a predetermined normal value of unidirectional voltage which will cause a predetermined normal safe current to flow in the device depending upon the temperature of the device, comprising a magnetizing circuit, 15 means for connecting the device in said magnetizing circuit and to a source of power to impress on the magnet a voltage higher than said normal value of voltage, means operable upon the magnetizing current in the magnet reaching the 20 value of said normal current to reduce the voltage impressed on said magnet approximately to said normal value of voltage, a discharge circuit,

5

10

15

20

25

including a resistor, means for connecting said magnet in said discharge circuit in series with said resistor, and in a reverse direction to said source to impress said normal value of voltage on said discharge circuit and for subsequently interrupting said magnetizing circuit, means responsive to an electrical condition of said discharge circuit for increasing the voltage impressed thereon to a voltage higher than said normal value of voltage, and means responsive to a different electrical condition of said discharge circuit for interrupting said discharge circuit.
